UNITED STATES PATENT OFFICE.

RICHMOND S. HAYES, OF JAMESTOWN, NEW YORK.

DESIGN FOR A SIGNAL-LIGHT CASING.

Application filed March 26, 1927. Serial No. 21,361. Term of patent 14 years.

To all whom it may concern:

Be it known that I, RICHMOND S. HAYES, a citizen of the United States, residing at Jamestown, in the county of Chautauqua and State of New York, have invented and produced a new, original, and ornamental Design for a Signal-Light Casing, of which the following is a specification, reference being had to the accompanying drawing, forming part thereof, and in which—

Fig. 1 is a front elevation of my newly designed signal light casing; and

Fig. 2 is a side elevation of the design shown in Fig. 1.

I claim:

The ornamental design for a signal light casing as shown.

RICHMOND S. HAYES.
